WINDOW HEADRAIL

Donn C. Blanchard, Miami, Fla., assignor to Denison Corporation, North Miami, Fla., a corporation of Florida

Application April 19, 1954, Serial No. 30,059

Term of patent 14 years

(Cl. D54—2)

To all whom it may concern:

Be it known that I, Donn C. Blanchard, a citizen of the United States, residing at Miami, county of Dade and State of Florida, have invented a new, original, and ornamental Design for a Window Headrail, of which the following is a specification, reference being had to the accompanying drawing, forming a part thereof.

I claim:
The ornamental design for a window headrail, as shown.
